ELI BROTHERS, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

UPPER-PULLING MACHINE.

1,289,632.

Specification of Letters Patent.

Patented Dec. 31, 1918.

Application filed August 21, 1915. Serial No. 46,662.

To all whom it may concern:

Be it known that I, ELI BROTHERS, a citizen of the United States, residing at Lynn, in the county of Essex and State of Massachusetts, have invented certain Improvements in Upper-Pulling Machines, of which the following description, in connection with the accompanying drawing, is a specification, like reference characters on the drawings 10 indicating like parts in the several figures.

This invention relates to upper pulling machines and is herein shown for illustrative purposes as embodied in an apparatus adapted for use in pulling a shoe upper 15 preparatory to presentation of the shoe to a pulling-over machine, although many portions of the invention are adapted for use in other upper pulling machines. It is well understood that under many shoe manufacturing conditions as, for example, when uppers are scant or small for the last, or when the last is peculiarly shaped, the upper requires to be pulled to locate it in such relation to the last that the 20 pulling-over machine grippers can conveniently seize the edge of the upper. Another reason for this preliminary operation is that by pulling the loose upper forwardly on the last before it is subjected to the pulling-over operation, the upper materials are made to set more snugly to the rear part of the last and a better fitting shoe is produced. This preliminary pulling was formerly done with hand pincers, but superior results are now obtained by the use 25 of the apparatus forming the subject-matter of United States Letters Patent No. 1,139,613 granted May 18, 1915, on application of P. J. Wentworth. In one of its aspects the present invention is an improvement on said apparatus in that it provides means for preliminarily stretching the upper transversely as well as longitudinally, the construction shown comprising means for 30 pulling the upper at opposite sides of the forepart while it is held under longitudinal pulling tension. This has the advantage of drawing the upper down to the last between the instep and the toe where it otherwise usually bridges more or less, and also the advantage of bringing the portion of the upper which is to be seized by the side grippers of the pulling-over machine into such relation to the edge of the last that said grippers can

conveniently engage the upper. The use of 55 this invention saves time of the pulling-over machine operator in getting the upper properly gripped, and such use also enables scanner uppers to be successfully employed than would otherwise be possible because 60 the upper is in effect stretched twice, transversely as well as longitudinally, going to the pulling-over machine after the preliminary stretching.

A further feature of the invention consists in the combination with a toe gripper of a bottom rest movably mounted to permit the shoe to be moved manually relatively to the gripper in a direction to pull the upper longitudinally. In the construction 70 shown the bottom rest is mounted to swing about an axis so disposed relatively to the shoe that the shoe is not only tipped but is carried bodily backward from the toe gripper by the movement of the rest in response 75 to pressure of the operator's hand upon the shoe. Effective means is thus provided for straining the upper longitudinally without undue friction upon the peripheral surface of the last. Combined with means for pulling the upper transversely, such longitudinal upper pulling means has further important advantages in that it affords the operator an opportunity to proportion the longitudinal pull to the transverse pull as the operation on the work progresses by tipping the shoe, for example, toward the toe gripper to relax in some degree the longitudinal tension; and by tipping the shoe in this manner, moreover, the operator may cause the side 80 grippers to pull the upper backward slightly over the ball of the last to insure a better fit at this portion of the shoe when the shoe is lasted.

Other important features of the invention 95 consist in novel gripper controlling means and in certain novel details of construction and combination of parts exemplified in the illustrated machine. The invention will be more fully described in connection with the 100 accompanying drawings and then will be particularly pointed out in the claims.

Figure 1 of the drawing is a rear elevation of the illustrative machine, one side gripper mechanism being shown in section.

Fig. 2 is a side elevation, one side gripper being omitted to show the shoe rest.

The machine shown comprises a frame

having a table 2 which is adapted to rest on a work bench and is channeled to provide straight longitudinal and transverse dovetailed guide-ways 3 and 4 in which toe and side grippers are adjustable independently toward and from each other for adaptation to sizes of shoes. Adjustment of each gripper is maintained by a thumb screw 5 extending through a cap plate 6 and threaded into the foot plate 8 of the gripper, said plates embracing and clamping upon a rib 9 at each side of the guideway. These grippers are stationary, or substantially stationary, during the operation of the machine and the last is moved relatively to them.

From the foot plate 8 of each gripper rises a relatively fixed gripper bar 10 which is channeled vertically as shown in section in Fig. 1 and has affixed to its upper end a jaw 12. A coöperating jaw 14 is pivoted to bar 10 and has a tail piece overlaid by a roller 15 on the upper end of a jaw operating bar 16 which is movable up and down in the channel of bar 10. The jaw operating bar is vertically slotted to receive a closing spring 18 which is confined under compression between the lower end of the slot in the bar and a cross-plate 19 supported by bar 10 and a cover plate 20.

Each jaw operating bar 16 is engaged at its lower end by a lifting lever 25. This lever is fulcrumed to the frame below the table 2 and has a slotted end embracing a roll on the lower end of the bar 16. Lever 25 is engaged on its lower side by an operating lever 26 which is fulcrumed to the frame at 27 and has a roll on its upper end and a laterally inclined face on its lower end. The lower end of lever 26 engages a vertically movable operating head 30 on a rod 32 which is arranged to be lifted by a treadle 35 and returned downwardly by a spring 34.

Both of the side grippers shown in the drawings and the toe gripper are constructed and operated in the same way as the gripper just described, the lever 26 for each gripper engaging the adjacent side of the operating head 30. This operating head and spring 34 normally maintain the levers in the position shown in Fig. 1 with the gripper jaws open. By depressing the treadle 35 the head 30 can be raised above the contacting ends of levers 26 and then the closing springs 18 are allowed to operate to depress the jaw operating bars 16 and effect gripping of the shoe upper. By releasing the treadle the spring 34 is allowed to act for depressing the operating head 30 and turning the levers 26 and 25 to lift the jaw operating bars to the position shown in Fig. 1, where the jaws 14 swing open by gravity.

The operating head 30 has anti-friction

rolls 31 to facilitate the actuation of levers 26. It will be seen by comparison of Fig. 1 and Fig. 2 that the roll 31 which engages the toe gripper lever 26 is located higher on the head than the rolls which engage the side gripper levers 26. The head is also cut away below the toe gripper roll 31. The result is that as the head 30 is raised the toe gripper lever 26 is allowed to turn under the influence of the closing spring 18 before the side gripper levers, and the toe gripper to close while the side grippers are still maintained open.

The rod 32 is extended above the head 30 to provide a support for a shoe rest adapted to engage the bottom of a shoe presented to the grippers. The parts are so arranged that the rod and the shoe rest are initially below shoe engaging position and when the toe gripper is closed the rod arrives in position to constitute an abutment about which the last can be rocked to effect longitudinal pulling of the upper to set it forwardly about the heel part of the last and draw it down the inclined instep face of the last. To facilitate this use the shoe resting member 40 is connected to the rod by a pivot 42 which is offset forwardly from the rod 32. A spring 44 and shoulders below the pivot hold member 40 upright and an adjustable stop 45 limits its rearward tipping movement. With this arrangement downwardly and backwardly directed force applied by the workman to the rear part of the last will cause the member 40 and the last to move about the pivot 42, the entire last having a component of backward movement away from the toe gripper. It has heretofore been proposed to arrange for rocking a last about a stationary abutment, as in my prior Patent No. 1,135,945, and to arrange for sliding a last directly backwardly away from toe grippers, as in Patent No. 1,118,965. The backward and rocking movement here provided combines the advantages of both prior arrangements and is broadly novel as I am advised.

The operator maintains his foot upon the treadle while the upper is being pulled longitudinally by manipulation of the last, thus enabling him to raise or to lower the last relatively to the side grippers which are standing open to receive the upper, and the last can also be turned laterally to proportion the longitudinal pulling strain as desired between the two sides of the upper. When the operator desires to do so, he will close the side grippers by a further depression of the treadle. It should be understood that the side gripper operating means and the bottom rest are so arranged that the side grippers will always close before the rest will have raised the last too high for the grippers to engage the upper, the machine being free and open around the bottom rest

between the side grippers and in the rear of them to permit the above-described manipulations of the last to pull the upper longitudinally while the shoe and rest are in a 5 lower position than that at which the side grippers will close. After the side grippers have closed the bottom rest 40 may be further raised to force the last upwardly into the upper and draw the upper down to the 10 last where it may have been bridged from the instep to the toe during the longitudinal pulling of the upper. By tipping the last forwardly about pivot 42, excessive longitudinal stretching of the upper will be 15 avoided while the upper is being stretched transversely by the elevation of the bottom rest 40. Such forward tipping movement of the last relatively to the side grippers tensions the upper backwardly to a slight 20 extent over the ball of the last and against the base of the instep and causes it to fit better over the ball of the last when the shoe is lasted. The guideway for the toe gripper is of sufficient length to permit adjustments 25 for engaging the sides of the upper by the side grippers at any desired points between the toe and the instep of the last.

It will be evident from the foregoing description that by this invention a machine is 30 provided by which an upper may be pulled longitudinally to set it about the heel part of the last and then also pulled transversely to draw it down to the top face of the last between the toe and the instep, which latter 35 result could not be obtained in the pulling mechanism of Patent No. 1,139,613. Furthermore, the possibility of turning and tipping the last upon the bottom rest relatively to the side grippers permits correct adjustments 40 of the initially tensioned upper upon the last, including straightening and positioning the tip seam, to be obtained before the upper is seized by the grippers of the pulling-over machine and thereby increases 45 the capacity of that machine.

Another respect in which the use of this invention is valuable is that the side grippers pull the upper down to the last and pull the edges of the upper into position for convenient engagement by the pulling-over machine grippers. Time is lost in positioning the edges of many styles of uppers in the side grippers of the pulling-over machine because the upper is bridged from the instep 50 to the toe and does not reach to the edge of the last at the sides when the shoe is presented to the pulling-over machine. This loss of time is saved by the use of this invention. In fact, the preliminary stretching 55 of the upper effected by this machine makes it possible successfully to pull over shoes on the pulling-over machine which are cut so scant that they can not be seized by the grippers of the machine until after being subjected to the operation of this new 60

machine. In this way an economy in upper stock can be effected which alone pays for the cost of operating this machine, and the twice pulled shoe retains its shape better than the shoe having the larger upper and 70 pulled to a less extent.

The improvement in methods of making shoes herein disclosed is not claimed in this application but in a divisional application, Serial No. 246,522, filed on July 24, 1918. 75

Having described the invention I claim as new and desire to secure by Letters Patent of the United States:—

1. An upper pulling machine having, in combination, a rest to sustain a shoe with its sole face downward, toe and side grippers, a table having guideways in which the side grippers are adjustable bodily toward and from each other and the toe gripper is adjustable bodily toward and from the side 85 grippers, and operating means organized to permit longitudinal stretching of the upper by use of the toe gripper and thereafter to effect transverse stretching of the upper by use of the side grippers. 90

2. An upper pulling machine having, in combination, a rest to sustain a shoe with its sole face downward, toe and side grippers, and operating means constructed and arranged to permit longitudinal stretching 95 of the upper by use of the toe gripper and the shoe rest before the side grippers seize the upper and thereafter to effect transverse stretching by use of the side grippers, said rest being movable by the operator to control the extent of longitudinal stretching 100 of the upper independently of the extent of the transverse stretching as the operation of the machine progresses.

3. An upper pulling machine having, in 105 combination, a rest to sustain a shoe with its sole face downward, and toe and side grippers, the shoe rest being pivoted under the shoe at the rear of the toe end for tipping movement longitudinally of the shoe to carry 110 the shoe rearwardly from the toe gripper.

4. An upper pulling machine having, in combination, a rest to sustain a shoe with its sole face downward, and a toe gripper, the sole rest being pivotally supported and the 115 machine being constructed to permit the shoe to be tipped about said pivotal support of the rest as a fulcrum for giving the last a bodily movement backwardly and raising its toe relatively to the toe gripper to stretch 120 the upper longitudinally.

5. An upper pulling machine having, in combination, a toe gripper, and a fulcrum rest for the shoe pivotally supported below the shoe and arranged to permit the shoe to 125 be tipped manually relatively to the gripper about the point at which the rest is supported.

6. An upper pulling machine having, in combination, a toe gripper, and resting 130

means upon which the shoe can be fulcrumed, said resting means being constructed and arranged for movement to effect a bodily tipping movement of the shoe longitudinally away from the toe gripper in response to pressure of the operator's hand upon the shoe.

7. An upper pulling machine having, in combination, relatively movable gripping jaws adapted to receive the margin of an upper when the shoe is presented thereto in the hand of a workman, and a sole rest constructed and arranged for movement with the shoe in response to pressure of the workman's hand upon the shoe to tension the upper on the last, said parts being constructed and arranged to effect a relative bodily movement of the last and the gripping jaws longitudinally of the shoe to tension the upper.

8. An upper pulling machine having, in combination, relatively movable gripping jaws adapted to receive the margin of an upper when the shoe is presented thereto in the hand of a workman, and a sole rest about which the shoe may be turned by pressure of the workman's hand upon it to tension the upper on the last, said rest comprising a supporting member and a shoe engaging member pivotally connected to the supporting member substantially opposite to the ball portion of the shoe and arranged to cause longitudinal bodily movement of the shoe away from the gripping jaws when the shoe is turned on the rest to tension the upper.

9. An upper pulling machine having, in combination, a shoe rest, a gripper, a gripper jaw closing spring operatively connected with the jaws of the gripper, and operating means constructed and arranged to be operated manually to open the jaws and hold the closing spring under compression and also for manual manipulation to release the closing spring, said operating means being also connected to the shoe rest for moving said rest relatively to the gripper.

10. An upper pulling machine having, in combination, a shoe rest, a gripper, a spring to close the gripper, a stronger spring normally holding the gripper open, and means for rendering the stronger spring operative or inoperative.

11. An upper pulling machine having, in combination, a shoe rest, a plurality of grippers, a closing spring for each gripper, an opening spring adapted to overcome the closing springs, and operating means arranged to overcome the opening spring and to control the times at which the several closing springs shall act.

12. An upper pulling machine having, in combination, a shoe rest, toe and side grippers, a closing spring for each gripper, an opening spring adapted to overcome the

several closing springs, and operating means 65 adapted for movement to overcome the opening spring and constructed and arranged to restrain the side grippers from closing while the toe gripper closes.

13. An upper pulling machine having, in combination, a shoe rest, a gripper, a closing spring operatively connected with the gripper jaws, an operating bar arranged to be depressed by the spring to close the gripper, a lever having a lifting connection with the bar, and a treadle-operated rod having a head formed and arranged to hold the lifting lever at rest with the gripper open and to permit movement of the lever allowing the closing spring to act when the treadle 80 rod is raised.

14. An upper pulling machine having, in combination, a shoe rest, a gripper, a closing spring operatively connected with the gripper jaws, an operating bar arranged to 85 be depressed by the spring to close the gripper, a lever fulcrumed at one end and having a sliding connection at its other end with the bar, a second lever fulcrumed between its ends and having a traveling connection with the first lever to raise the bar, a treadle-operated rod having a head arranged to engage and operate the second lever, and a spring arranged to hold the treadle rod in the position to maintain the 95 gripper open.

15. An upper pulling machine having, in combination, a shoe rest, side grippers, gripper closing springs, and gripper opening means including two levers associated respectively with the two side grippers and having opposed arms and a treadle-operated controller movable between said opposed lever arms.

16. An upper pulling machine having, in combination, a shoe rest, side grippers, a toe gripper, and gripper operating means including a lever associated with each gripper and having an inwardly directed arm and a controller engaged on three sides by 105 the gripper levers and constructed and arranged to cause the operation of the toe 110 gripper and side grippers successively.

17. An upper pulling machine having, in combination, a shoe bottom rest, a gripper, a closing spring for the gripper, means to hold the spring from closing the gripper, and manual means to release the closing spring and to operate the bottom rest to move the shoe last away from the gripper 120 for stretching the upper while the gripper remains substantially stationary.

18. An upper pulling machine having, in combination, a shoe bottom rest, a toe gripper, side grippers, separate closing devices 125 for the toe and side grippers, and means for moving the bottom rest to force the last away from the grippers, said means being con-

structed and arranged to cause the closing of the toe gripper upon the upper to be effected and then a movement of the bottom rest followed by closing of the side grippers and further movement of the bottom rest to stretch the upper.

19. An upper pulling machine having, in combination, a shoe bottom rest, toe and side grippers and operating means constructed and arranged to close the toe gripper, advance the rest in a direction to move the last for stretching the upper held by the toe gripper, and then close the side grippers and further move the rest for stretching the upper held by the side grippers.

20. An upper pulling machine having, in combination, a shoe bottom rest, gripping means arranged to engage the upper at the side and toe of a last, means for causing the toe gripping means to seize the upper, said shoe bottom rest being constructed to permit the last to be tipped manually to stretch the upper lengthwise between the toe gripping means and the last, means to cause the side gripping means to seize the upper, and means for moving the last with relation to the side gripping means to stretch the upper transversely.

21. An upper pulling machine having, in combination, downwardly acting side and toe grippers, a last bottom rest and operating means all constructed and organized to permit a shoe to be presented to the machine sole face downwardly with its toe pointing away from the operator, said operating means being constructed to cause the upper to be seized by the toe gripper and then to permit the last to be moved with the aid of the last rest relatively to the toe gripper to stretch the upper longitudinally and subsequently to cause the sides of the upper to be seized by the side grippers and the last to be raised by the bottom rest to stretch the upper transversely while the operator controls the angular relations of the last to the last rest and grippers.

22. An apparatus for pulling an upper preparatory to presentation of the shoe to a pulling-over machine having, in combination, means to pull the upper forwardly on the last, said means operating to cause the upper to bridge from the instep to the toe of the last, and means arranged for use after the forward pull has been effected and while the upper is held under tension for pulling the upper transversely to draw it down to the last between the instep and the toe, said apparatus being constructed to permit the operator to vary at will the forward tension of the upper relatively to the transverse tension during the transverse pulling operation.

23. An apparatus for pulling an upper preparatory to presentation of the shoe to a pulling-over machine having, in combina-

tion, means to pull the upper forwardly on the last, said means operating to displace relatively to the edges of the ball of the last those portions of the edge of the upper which are to be seized by the side grippers of the pulling-over machine, grippers for seizing said portions of the edge of the upper, and means for moving the last away from said grippers while the grippers are substantially stationary to pull the edges of the upper into position for more convenient engagement by the pulling-over side grippers.

24. An apparatus for pulling an upper preparatory to presentation of the shoe to a pulling-over machine having, in combination, a toe gripper and a tilting shoe bottom rest in position to receive a shoe with its sole down and its top face before the operator and constructed for use in pulling the upper forwardly on its last through a backwardly tipping movement of the last, and means arranged for operation while the forward pull is maintained for drawing the sides of the upper into a relation to the edge of the last to be conveniently engaged by the pulling-over side grippers, said parts being constructed and arranged to hold the shoe so that the operator can grasp it by the top face and with his hand hold the upper substantially in pulled relation to the last while releasing the shoe from the apparatus and presenting it to the pulling-over machine.

25. An apparatus for pulling an upper preparatory to presentation of the shoe to a pulling-over machine having, in combination, a toe gripper and a last bottom fulcrum rest arranged to receive a shoe and stretch the upper longitudinally with the toe of the shoe toward the rear of the machine, said rest being constructed to permit the shoe to be tipped relatively to the toe gripper to stretch the upper, and side grippers arranged to engage the sides of the upper and stretch it transversely across the last after the upper has been stretched longitudinally.

26. An apparatus for pulling an upper preparatory to presentation of the shoe to a pulling-over machine having, in combination, a toe gripper and a last bottom fulcrum rest arranged to receive a shoe and stretch the upper longitudinally, side grippers arranged to engage the edges of the longitudinally stretched upper at the will of the operator, and means for operating the fulcrum rest to raise the last and effect stretching of the upper transversely across the last by the side grippers.

27. An upper pulling machine having, in combination, a toe gripper, a fulcrum rest between which and the gripper the upper of a shoe on a last may be stretched longitudinally by manipulation of the last, side grippers, and means for operating the rest after the upper has been stretched longitudinally

to move the last relatively to the side grippers for stretching the upper transversely across the last.

28. An upper pulling machine having, in combination, a toe gripper, for engaging an upper on a last, a fulcrum rest movable relatively to the gripper to permit the upper to be stretched longitudinally by a manually effected movement of the last, side grippers, and means for relatively moving the side grippers and the last to stretch the upper transversely across the last, the machine being free and open around the bottom rest between the side grippers and in the rear of them to permit manipulations of the last to pull the upper longitudinally while the shoe and rest are located in upper seizing relation to the side grippers.

29. An upper pulling machine having, in combination, grippers for engaging an upper at the toe and at opposite sides of a last, a shoe bottom rest, and operating means constructed and arranged to permit longitudinal stretching of the upper by the toe gripper through movement of the last and the shoe rest independently of said operating means before the side grippers seize the upper and thereafter to effect transverse stretching by use of the side grippers.

30. An upper pulling machine having, in combination, grippers for engaging an upper at the toe and at opposite sides of a last, a shoe bottom rest, and means for effecting relative movement of said grippers and bottom rest to pull the upper both longitudinally and transversely, said bottom rest being movable in response to pressure of the shoe about an axis extending laterally of the shoe to permit the operator to proportion the longitudinal pull to the transverse pull as the upper pulling operation progresses.

31. An upper pulling machine having, in combination, toe and side grippers for engaging the upper of a shoe on a last, a shoe bottom rest movably mounted to permit the shoe to be tipped lengthwise by pressure of the operator's hand upon it while the upper is held by the toe gripper to pull the upper forwardly on the last, and means for subsequently effecting relative movement of the last and the side grippers for pulling the upper transversely.

32. An upper pulling machine having, in combination, grippers for engaging an upper at the toe and at opposite sides of a last, a movable shoe bottom rest, and manual means for effecting relative movement of said grippers and bottom rest to pull the upper, said parts being so constructed as to permit the operator by movement of said rest to tip the shoe in either direction at will about an axis extending laterally of the shoe as the upper pulling operation progresses.

33. An upper pulling machine having, in combination, grippers for engaging an upper

at opposite sides of a last, a shoe bottom rest, and means for effecting relative movement of said grippers and the bottom rest to pull the upper transversely, said bottom rest being movable in response to pressure of the shoe to permit the operator to tip the last bodily forward relatively to the side grippers to cause said grippers to pull the upper rearwardly on the last.

34. An upper pulling machine having, in combination, a toe gripper, and a shoe bottom rest pivotally mounted to swing about an axis extending laterally of the shoe, the axis of said rest being so disposed relatively to the rest and to the toe gripper as to cause pressure of the operator's hand upon the rear part of the shoe to swing the shoe and the rest together in a direction to carry the toe end of the shoe diagonally rearward from the toe gripper.

35. An upper pulling machine having, in combination, a toe gripper, and a shoe rest arranged relatively to said gripper to engage the bottom of the shoe at the forepart, said rest being mounted to swing about an axis extending laterally of the shoe and in such relation to the shoe engaging portion of the rest as to cause the rest to be swung in response to pressure of the shoe in a direction to carry the toe end of the shoe upwardly and backwardly from the toe gripper.

36. An upper pulling machine having, in combination, a gripper for engaging an upper at the toe end of a last, and a shoe bottom rest pivoted to swing about an axis substantially opposite to the ball of the last for tipping the shoe rearwardly away from the toe gripper to pull the upper.

37. In an upper pulling machine, a gripper comprising gripper jaws and a closing spring, spring operated mechanism for overcoming said closing spring to permit the jaws to open, and means for operating said mechanism to release the closing spring for closing the jaws.

38. An upper pulling machine having, in combination, a rest for engaging the bottom of a shoe on a last, an upper engaging gripper, a closing spring for said gripper, operating means for moving the bottom rest to force the last away from the gripper to pull the upper, and mechanism arranged to be controlled by said bottom rest operating means for releasing said closing spring to permit the gripper to close upon the upper.

39. An upper pulling machine having, in combination, a shoe rest, a stationary gripper support, grippers mounted on said support to slide bodily toward and from the shoe rest for adjustment to different shoes, means for securing the grippers on the support in adjusted position, and means for moving the shoe rest to cause the upper to be pulled by the grippers.

40. An upper pulling machine having, in

combination, a shoe rest, a stationary gripper support provided with guideways, toe and side grippers adjustable along said guideways toward or from the shoe rest each 5 independently of the others, means for securing the grippers to the support in adjusted position, and means for moving the shoe

rest to cause the upper to be pulled by the grippers while the grippers are held stationary.

10

In testimony whereof I have signed my name to this specification.

ELI BROTHERS.
